UNITED STATES PATENT OFFICE.

MATTHEW L. HOYT, OF LITTLE FALLS, NEW YORK, ASSIGNOR TO D. H. BURRELL & COMPANY, OF LITTLE FALLS, NEW YORK.

DESIGN FOR A FRAME FOR CENTRIFUGAL MACHINES.

41,009.

Specification for Design.

Patented Nov. 29, 1910.

Application filed October 16, 1909. Serial No. 523,089. Term of patent 14 years.

To all whom it may concern:

Be it known that I, MATTHEW L. HOYT, a citizen of the United States, residing at Little Falls, in the county of Herkimer and State of New York, have invented a new, original, and ornamental Design for Frames for Centrifugal Machines, of which the following is a specification.

The accompanying drawing represents a perspective view of a frame embodying this design.

The design comprises an upwardly tapering pedestal A consisting of two upwardly

converging legs having their upper portions connected by an arch and a circular top B resting thereon, a bulbous middle portion C mounted on said circular top, and a column D rising from this middle portion.

I claim:

The ornamental design for a frame of a centrifugal machine, substantially as shown and described.

MATTHEW L. HOYT.
